UNITED STATES PATENT OFFICE.

SHUBAEL COTTLE, OF NEW YORK, N. Y.

BRACELET.

SPECIFICATION forming part of Letters Patent No. 243,218, dated June 21, 1881.

Application filed May 7, 1881. (No model.)

To all whom it may concern:

Be it known that I, SHUBAEL COTTLE, of the city, county, and State of New York, have invented a new and useful Improvement in 5 Bracelets; and I do hereby declare that the following is a full, clear, and exact description of the same, reference being had to the accompanying drawings, forming part of this specification, in which—

10 Figure 1 is a perspective view of the bracelet, showing in dotted lines its opened position. Fig. 2 is a longitudinal section through the swivel-joint. Fig. 3 is a detail view of the pintle-tube. Fig. 4 is a cross-section through the line $x x$ of Fig. 2. Fig. 5 shows detail views, in perspective, of the thimbles.

15 My invention relates to an improved form of bracelet of that general construction in which several tubular parts with swiveling joints are combined with a torsional spring arranged within the same, whose tension serves to hold the sections of the bracelet in an elliptical form, but allows them to be opened by a lateral movement for the insertion of the wrist.

20 25 My improvement consists in making the bracelet in two hollow sections with their terminals and swivel-joints both in the minor axis of the ellipse, and combining them with a torsional spring within, and also in the peculiar form of swivel-joint, as will be hereinafter more fully described.

30 35 In the drawings, A A' represent the two sections of my bracelet, which are made hollow and connected by a single swivel-joint at a , so as to form an elliptical bracelet. This swivel-joint a , and also the gate or separable joint formed by the lapping terminals of the bracelet, lie diametrically opposite each other in the minor axis of the ellipse. Within this bracelet 40 and extending through both hollow sections is an elliptical spring, B, whose tension causes the two sections to normally occupy the form of an ellipse, but which permits the two lapped ends of the sections to be opened away from each other laterally, as shown in dotted lines in Fig. 1, to permit the introduction or removal of the wrist.

45 50 To connect the adjacent ends of the sections to form the swivel-joint, I fix in the adjacent ends of said tubular sections straight thimbles C C', which have transverse slots cc' . (See

Fig. 5.) These thimbles are suitably stayed and secured in the curved ends of the tubes, so as to have a common axial relation, and the adjacent edges of the tubes and thimbles are 55 suitably faced to form bearing-surfaces.

Extending through both of the thimbles C C' is a straight pintle-tube, D. This pintle-tube has, at its opposite ends, and preferably upon opposite sides, projecting lugs $d d'$, which 60 enter the slots cc' of the thimbles and prevent the two sections of the bracelet from moving apart. These lugs I preferably form by stamping in the tube tongues e , and then turning up the ends of the same to form the lugs, 65 as shown in Fig. 3. The tubular character of the pintle D, it will be seen, gives passage to the torsion-spring B; and its lugs $d d'$, in addition to their function of holding the bracelet-sections together, act as stops to limit the 70 amount of lateral deflection between the two parts A A' of the bracelet. Thus, when the two ends of the bracelet are turned away from each other, the lugs $d d'$ traverse the slots cc' until they reach the end of the same, when they act 75 as stops to prevent further movement.

In defining my invention more clearly I would state that I am aware that a bracelet has heretofore been constructed of a semi-elliptical tube and two quadrantal pieces made hollow and combined with an inner torsional spring. My invention is distinctive with respect to this in the following respects: First, I have but one common axis for the movable sections of my bracelet, which makes the latter simpler and stronger; and, secondly, this swivel-joint being located at the minor axis of the ellipse, it is removed from contact with the more or less angular bones of the wrist, and it cannot therefore pinch the wearer in putting 80 it on or off, and if an ornamental bead or edging should be made at this joint it does not interfere with the comfort of the wearer, as it would if located at the smaller parts of the wrist or in the line of the major axis of the 85 ellipse.

Having thus described my invention, what I claim as new is—

1. An elliptical bracelet composed of two hollow sections connected together by a swivel-joint located in the minor axis of the ellipse, 100 and a torsional spring located inside the brace-

let and extending through both sections, all combined substantially as and for the purpose described.

2. The combination, with the adjacent ends 5 of the tubular sections of a bracelet, of the fixed thimbles C C', having transverse slots c c', the tubular pintle D, arranged within and connecting the thimbles and having lugs d d' entering the slots of the thimbles, and the tor-

sional spring D, passing through said tubular 10 pintle, substantially as and for the purpose described.

The above specification of my invention signed by me this 27th day of April, 1881.

SHUBAEL COTTLE.
